EXPANSIBLE CONTAINER

Nathan Ottinger, New York, N. Y.

Application March 16, 1934, Serial No. 715,813

7 Claims. (Cl. 150—7)

This invention relates to expandable containers and more particularly to containers of the bellows type.

It is the principal object and purpose of my invention to dispense with the use of tie strings or other supplemental fastening devices and provide a closure means for the container which will automatically accommodate itself to variations in bulk of the contents of the container.

16 In a preferred embodiment I provide the front wall of the container with an exterior downwardly opening pocket extending across the width thereof. A cover or closure flap extends from the upper edge of the rear wall and is divided by 18 spaced parallel scores into a plurality of relatively flexing sections. By inserting one or more of these flap sections upwardly into the pocket, depending upon the extent of expansion of the container by its contents, the flap is securely held 20 in position to completely close the open top of the container body.

Another object of the invention is to provide 25 convenient means securely attached to the end of the closure flap whereby the flap sections may be easily withdrawn from the pocket to open the container.

It is also a further object of my invention to 30 provide a container of this character which is strong and durable, simple and inexpensive in construction, and highly serviceable in practical use.

With the above and other objects in view the invention consists in the improved expandable container and in the form, construction and relative arrangement of its several parts as will be 35 more fully described, illustrated in the accompanying drawing and subsequently incorporated in the subjoined claims.

In the drawing wherein I have disclosed one 40 simple and practical embodiment of the invention, and in which similar reference characters designate corresponding parts through the several views,—

Fig. 1 is a perspective view showing the container closed.

Fig. 2 is a similar view with the closure flap in open position.

Fig. 3 is an enlarged vertical sectional view taken on the line 3—3 of Fig. 1.

Fig. 4 is a fragmentary horizontal sectional view taken on the line 4—4 of Fig. 2.

Fig. 5 is a detail fragmentary section on an enlarged scale showing the co-acting locking means for the closure flap.

55 Referring in detail to the drawing in the illus-

trated example, the front wall 5 and the rear wall 6 of the container each preferably consists of a sheet of paper, leather or other material of suitable dimensions. These walls are connected at their bottom and opposite end edges by the bellows folds 7, preferably of paper, leather, linen or other textile material. The edges of these bellows folds are securely attached by any suitable means to the walls 5 and 6.

As herein shown a strip of paper or other flexible material 9 is attached to the inner surface of the front wall 5 along the upper edge thereof and folded outwardly and downwardly to provide the part 10 thereof cooperating with the wall 5 to form a downwardly opening pocket 15 extending across the width of said front wall. The part 10 has a lower edge 11 turned upwardly upon the inner face of said part to provide a rounded lower edge on the pocket wall. End extensions 12 of the part 10 are turned rearwardly upon the front sections of the bellows folds 7 and secured thereto to close the pocket at its opposite ends. If desired, instead of forming this pocket from a separate piece it may be formed from an integral extension of the front 20 wall 5 of the envelope.

The rear wall 6 is extended beyond the open top of the envelope body as at 13 to form the closure flap generally indicated at 15.

This flap is heavily scored along spaced parallel longitudinal lines shown at 16 to provide a plurality of narrow relatively flexing sections 17.

Preferably the closure flap 15 is provided with a pull tab 18. While this tab may be attached 35 to the closure flap in various ways, a strong and secure connection is obtained by providing the flap in spaced relation to its free longitudinal edge, with a slot 19 and projecting the tab outwardly therethrough until the shoulders 20 40 formed by lateral extensions on one end of the tab abut against the inner face of the flap. The longitudinal edge portion 21 of the flap is then turned over upon said extensions and adhesively secured thereto and to the inner face of the flap. 45 The connection of the tab with the flap is thus strongly reinforced and liability of the tab being torn away or disconnected from the flap is reduced to a minimum.

In the use of my improved container, after 50 the papers or other articles have been placed within the container the flap 15 is folded over the top thereof, such folding being facilitated by the scores 16 which obviate the formation of unsightly cracks in the surface of the closure 55

flap. After bending the tab 18 over upon the outer surface of the flap the free end of said flap is folded inwardly and upwardly into the horizontal pocket, the part 10 of which confines the 5 end of the flap closely against the front wall 5 of the container. The free end of the tab 18 protrudes beyond the open side of the pocket on the surface of the wall 5. The score 16 along which the flap is folded upwardly into the pocket 10 is selected in accordance with the degree of expansion of the container and coincides with the lower edge of the part 10 which yieldably grips the flap at said score as seen in Fig. 5 and acts to retain the flap 15 in closely folded position 15 over the open top of the container and upon the surface of the wall 10 of the pocket.

The length of the closure flap 15 is such that when the container body is expanded to full capacity one or more of the flap sections 17 may 20 be folded upwardly into the retaining pocket. Thus as seen in Figs. 1 and 2 of the drawing, I provide a container of the expanding type which may be easily, quickly and securely closed without the manipulation of tie strings or other 25 extraneous fastening means.

To open the container it is merely necessary to pull upon the tab 18 and the end of the closure flap 15 is thereby easily withdrawn from the retaining pocket so that access may be freely 30 had to the contents of the container.

My invention, as above described, has been found to be very serviceable in practical use. It will, of course, be understood that the container may be produced in numerous different 35 sizes to be used for a variety of purposes and the weight of the paper or other materials employed is determined in accordance to the particular use to which the container is to be applied. It will, however, be appreciated that the 40 described construction while simple and inexpensive, possesses maximum durability and will successfully resist internal or external strain tending to open the closure flap even when the container is more or less abusively handled.

While I have herein shown and described one simple and practical embodiment of my present improvements it is nevertheless to be understood that the same may be also incorporated in various other structural forms, and I accordingly 50 reserve the privilege of resorting to all such legitimate changes in the form, construction and relative arrangement of the several parts as may be fairly considered of the appended claims.

I claim:

1. In an expansible container having front and rear walls and expansible means connecting the bottom and opposite end edges of said walls; an external, downwardly opening pocket on said front wall, extending across the outer side thereof, 60 a closure flap extending from the upper end of said rear wall and foldable over the open top of the container and upon the wall of said pocket, said flap embodying means extending longitudinally of the pocket and enabling selected portions thereof of variable width to be inserted upwardly into the pocket, and said means cooperating with the lower edge of the pocket wall to prevent release of the closure flap and retain the same in closely superposed relation to the open top of the container.

2. In an expansible container having front and rear walls and expansible means connecting the bottom and opposite end edges of said walls; an external, downwardly opening pocket on said 70 front wall, extending across the outer side thereof,

of, a closure flap extending from the upper end of said rear wall and foldable over the open top of the container and upon the wall of said pocket, said flap embodying means extending longitudinally of the pocket and enabling selected portions thereof of variable width to be inserted upwardly into the pocket, and said means cooperating with the lower edge of the pocket wall to prevent release of the closure flap and retain the same in closely superposed relation to the open 10 top of the container, and manipulable means connected to the free end of said flap and operable to withdraw the same from said pocket.

3. In an expansible container having front and rear walls and expansible means connecting the bottom and opposite end edges of said walls; an external, downwardly opening pocket on said front wall, extending across the outer side thereof, a closure flap extending from the upper end of said rear wall and foldable over the open top 15 of the container and upon the wall of said pocket, said flap embodying means extending longitudinally of the pocket and enabling selected portions thereof of variable width to be inserted upwardly into the pocket, and said means co- 20 operating with the lower edge of the pocket wall to prevent release of the closure flap and retain the same in closely superposed relation to the open top of the container, and a finger tab centrally attached to the free end of said flap, par- 25 tially insertable therewith into the pocket to protrude from the open side of the latter whereby said portion of the closure flap may be withdrawn from the pocket.

4. In an expansible container having front and rear walls and expansible means connecting the bottom and opposite end edges of said walls; an external, downwardly opening pocket on said front wall, extending across the outer side thereof, a closure flap extending from the upper 30 end of said rear wall and foldable over the open top of the container and upon the wall of said pocket, said flap embodying closely contiguous, 35 parallel sections, extending longitudinally of the pocket and flexibly connected with each other, a 40 selected number of said sections being insertable upwardly into said pocket to retain the closure flap in closely superposed relation to the open 45 top of the container.

5. In an expansible container having front and rear walls and expansible means connecting the bottom and opposite end edges of said walls; an external, downwardly opening pocket on said front wall, extending across the outer side thereof, a closure flap extending from the upper end 50 of said rear wall and foldable over the open top of the container and upon the wall of said pocket, said flap being scored along parallel lines extending longitudinally of the pocket to provide 55 definite flexibly connected sections thereof, angularly movable relative to each other, whereby a selected number of said sections may be inserted upwardly into said pocket to retain the closure flap in closely superposed relation to the open 60 top of the container.

6. In an expansible container having front and rear walls and expansible means connecting the bottom and opposite end edges of said walls; an external, downwardly opening pocket on said 70 front wall, a closure flap, extending from the upper end of said rear wall and foldable over the open top of the container and upon the wall of said pocket, said flap being scored along parallel lines extending longitudinally of the pocket to 75

- provide definite flexibly connected sections there-
of, angularly movable relative to each other,
whereby a selected number of said sections may
be inserted upwardly into said pocket to retain
5 the closure flap in closed superposed relation to
the open top of the container, and releasing
means for said flap connected to the end section
thereof and protruding from the open side of
said pocket.
- 10 7. A container body having front and rear
walls and connecting walls between correspond-
ing edges of said front and rear walls, said body
being open along one edge thereof, an external
inwardly opening pocket extending across said

front wall, a closure flap extending from the
rear wall of said container, said flap in spaced
relation to its free end edges having a slot there-
in, a finger tab extending through said slot hav-
ing stop shoulders at one end projecting laterally
beyond opposite ends of the slot, the end edge
portion of the flap being folded upon said end of
the tab and secured to the flap, said free end of
the flap being insertable into said pocket to re-
tain the same in closed position, and said tab
projecting from the open side of the pocket for
releasing said flap.
